To all whom it may concern:

Be it known that I, Gordon Alexander Allan King, a subject of the King of Great Britain, residing at 99 Gloucester Court, Kew, in the county of Surrey, England, have invented a new, original, and ornamental Design for a Horseshoe, of which the following is a specification, reference being had to the accompanying drawing, forming part thereof, wherein:

The characteristic features of my new design reside in the provision of the cleft stops at the heel ends of the shoe arms and the quarter clips at the sides of the shoe arms, as shown.

I claim:
